UNITED STATES PATENT OFFICE.

WILLIAM BARTHOLOMEW AND FRITZ BALZER, OF CHICAGO, ILLINOIS, ASSIGNEES
TO TROY LAUNDRY MACHINERY COMPANY, LIMITED, OF CHICAGO, ILLINOIS, A
CORPORATION OF NEW YORK.

SAFETY-COVER.

1,006,523.

Specification of Letters Patent. Patented Oct. 24, 1911.

Application filed June 30, 1910. Serial No. 569,810.

To all whom it may concern:

Be it known that we, WILLIAM BARTHOLOMEW, citizen of the United States, and FRITZ BALZER, subject of the Emperor of Germany, residing at Chicago, county of Cook, State of Illinois, have invented certain new and useful Improvements in Safety-Covers, of which the following is a specification, reference being had therein to the accompanying drawing.

This invention relates to a safety cover and particularly to a construction whereby the power is controlled in the opening and closing of the cover which is locked during the operation of the machine.

The invention has for an object to provide a novel and improved construction by which the movement of the cover for opening or closing the same controls the power shifting mechanism while the cover is locked automatically in the movement of a driven part of the machine to which the cover is applied.

A further object of the invention is to provide means by which the shifting of a belt connection produces simultaneous movement of a brake so that the machine may be stopped, the cover lock released, and the cover automatically opened.

Other and further objects and advantages of the invention will be hereinafter set forth and the novel features thereof defined by the appended claims.

In the drawings—Figure 1 is a vertical section with parts in elevation showing the application of the invention; Fig. 2 is a rear elevation from the left of Fig. 1; Fig. 3 is a detail elevation of the locking connections; Fig. 4 is a detail plan of the cover; Fig. 5 is a vertical section on line 5—5 of Fig. 4; and Fig. 6 is a similar view on line 6—6 of Fig. 4.

Like numerals of reference refer to like parts in the several figures of the drawings.

The invention is adapted for application to any class of machine and to control any preferred power mechanism.

For the purpose of illustrating one application of the invention, it is here shown in connection with a centrifugal extractor in which the numeral 10 designates the bowl of any desired shape or construction which is

supported by the usual standard 11 and contains a basket 12 which is mounted upon the driving shaft 13 for rotary movement. 55 This shaft is provided with a driving pulley 14 at its lower portion adapted to receive the usual belt which is guided in its movement thereto by the pulleys 15 mounted upon the frame 16 at the rear of the extractor. The shaft 13 is provided with a governor mechanism 17 which is here shown as of the usual ball and link type having the sliding collar 18 normally held in raised position by the compression spring 19 surrounding the shaft 13. 60 65

Coöperating with a face of the driving pulley 14 is a brake shoe 20 which, as shown in Fig. 1, is mounted for rocking and yielding movement upon the end of the brake lever 21. The rocking movement is secured by the pivotal bearing at 22 while the yielding movement is obtained by the bolt 23 extended from the shoe 20 and carrying the tension spring 24. The brake lever 21 is 70 mounted upon a rock shaft 25 pivoted at 26 upon the base of the machine. This rock shaft has secured thereto a hand lever 27 which is disposed at one side of the machine and adapted to be held in its adjusted position by means of any ordinary latch construction 28 carried thereby and coöperating 75 with a fixed part of the machine. The rock shaft 25 has also secured thereto an operating lever 29 which is connected at its upper end with the long arm of a bell crank lever 30 by means of the slotted connection shown at 31 in Fig. 1. The short arm of this bell crank lever is connected by the rod 32 with the short arm of the crank lever 33 80 which is pivotally mounted at 34 upon a standard 35. The long arm of the lever 33 has a link 36 extended therefrom and connected to one of the belt shifting fingers 37. 85

The fingers are secured to the shifting rod 38 which is also provided with stops 39 to limit its movement in opposite directions. These fingers coöperate with a belt which is adapted to be shifted from the loose pulley 40 to the tight pulley 41, both of which are 90 carried by the countershaft 42 mounted in the bracket 43 for that purpose. The countershaft also carries a brake pulley 44 mounted to be engaged by the oppositely 95 100

- disposed brake shoes 45. These shoes are pivoted at the upper ends of the rods 46 which are slidably mounted in the casing 47 carried by the bracket 43. The lower ends 5 of the rods 46 are extended through the arms 48 which are secured upon the rock shaft 49 which is mounted in bearings 50 carried by the bracket 43. Surrounding the rods 46, and bearing against the upper faces of the 10 arms 48 are compression springs 51 which are held by the set-collars 52 secured to the rods 46. This provides a yielding pressure of the brake shoes 45 against the pulley 44. For the purpose of operating these shoes to 15 apply the brake as the power belt is shifted to the loose pulley 40, a lever 53 is extended from the rock shaft 49 and provided with a slotted connection at 54 with the operating lever 29.
- 20 The cover 55 is pivotally mounted at 56 (Fig. 4) and is adapted to be automatically opened when unlatched by means of a flexible connection 57 extended over a bearing roller 58 and provided with an operating weight 59. The cover is automatically 25 latched in closed position when the machine is operating and any desired connections for that purpose may be provided, a convenient form being here shown. In this 30 form, the pivoted latch 60 is mounted upon the cover as shown in Figs. 1 and 4 to engage a portion of the bowl 10 and a rod 61 extends therefrom and is provided at the rear with a slide 62 having a hinge or pivot 63 adapted to be brought into alignment 35 with the pivots 56 of the cover in order to permit the operation of the latter when the latch is in released position. The link portion 64 at the rear of the slide 62 is pivotally 40 connected at 65 with a rod 66 which is connected with the lever 67 mounted on a rock shaft 68 as shown in Figs. 3 and 4. The rock shaft 68 has also secured thereto a lever 69 from which a connecting rod 70 extends 45 to a lever 71 with which it has a loop connection at 72. This lever is mounted in a swivel bearing 73 carried by a bracket 74 upon the under face of the bowl 10. The inner end 75 of the lever 71 engages the movable member 18 of the governor mechanism and is thereby shifted when the machine is run at the proper speed to operate the cover latch to lock the cover and holds this latch in locked position to prevent its operation or 50 the opening of the cover while the machine is being operated. The mounting of the lever 71 upon a vertical pivot permits a lateral movement thereof which is necessary in connection with a centrifugal extractor 55 as in the preliminary rotation of this shaft, a lateral movement thereof occurs until the speed is sufficient to maintain it in a true vertical plane and this movement is permitted by the pivotal mounting of the lever 60 and also its connection with the looped lower 65 end 72 of the rod 70 extending to the cover latch.
- The cover 55 is provided at its pivotal edge with lugs 76 between which a connecting rod 77 is mounted, the opposite end of 70 said rod being pivotally connected to a bell crank lever 78 loosely mounted upon the rock shaft 68. The arm 79 of this lever is connected by a pivoted link 80 with a tube 81 which surrounds the rod 70 and is provided 75 at its lower end with a contact block 82 having an inclined face 83 adapted to engage and operate a locking bolt 84 mounted within a fixed part 85 of the machine frame. The block 82 is adapted to coöperate within 80 a guide or way 87 while the bolt 84 is guided by a bracket 87 and normally retracted from locking position by means of a spring 88 disposed between the fixed part 85 and a set-collar 89 upon the bolt. The bolt 84 when 85 shifted into locking position, as shown in Fig. 3, engages a collar or projection 90 carried by the rod 32 by which the belt shifter is actuated and prevents the operation of this shifter when the cover is opened to move 90 the block 82 downward as shown in Fig. 3. When this block is in raised position and the cover closed, the bolt is automatically retracted by the spring and the belt shifter may be operated by the hand lever 27. 95
- In the operation of the machine, when it is desired to start the operation thereof, the cover is closed and the hand lever shifted toward the rod in Fig. 1 which releases the brake from the driving shaft of the basket and also from the brake pulley on the countershaft and simultaneously shifts the belt from the loose to the tight pulley to start the driving of the shaft for the basket. The first movement of this shaft is lateral to 100 a true vertical plane and this is compensated by the pivotal mounting of the lever for operating the cover latch. As the speed of the driving shaft increases, it rotates in a true vertical plane and the governor thereon is operated to effect a locking movement of the latch upon the cover which is maintained so long as the machine is in operation. In order to open the cover, the operation of the machine must be stopped and this is 105 effected by a shifting of the hand lever into the position shown in Fig. 1 which applies the brakes and simultaneously shifts the belt to the loose pulley. As soon as the speed or rotation of the driving shaft is reduced, 110 the cover latch is automatically released by the governor and the cover automatically opened. When so opened, the locking bolt prevents further shifting of the belt and the cover must be closed in order to permit further operation of the machine. 115
- It will be seen that this construction presents an efficient and desirable construction by which the opening of the cover is prevented while the machine is in operation 120 125 130

as it is automatically retained in locked position at such times, while the shifting of the driving connection and the application of the brakes to the driven parts are controlled by the hand lever, the movement of which is prevented at any time when the cover is in open position. The construction therefore presents a safety cover which effectually prevents accidents or injury due to opening the cover while the extractor or other machine is in operation.

Having described our invention and set forth its merits what we claim and desire to secure by Letters Patent is—

1. In a safety device for a power driven machine, a rotating member and shaft, a cover for said member, a locking device for said cover, and means actuated by the rotation of said shaft for automatically securing said locking device in locked position while said member is being rotated.

2. In a safety device for a power driven machine, a rotating member and shaft, a cover for said member, a locking device for said cover, and means moving with said member and shaft for automatically securing said cover in locked position while said member is rotated.

3. In a safety device for a power driven machine, a casing, a basket mounted therein and provided with a driving shaft, a cover mounted upon said casing, a locking device for said cover, and means shiftable upon said driving shaft for automatically securing said cover in locked position while the basket is rotated.

4. In a safety device for a power driven machine, a driving shaft for said machine, a power controlling mechanism for said driving shaft, a cover member provided with a latch, and means carried by said driving shaft for automatically operating said latch.

5. In a safety device for a power driven machine, a driving shaft for said machine, a power controlling mechanism for said driving shaft, a cover member provided with a latch, means carried by said driving shaft for automatically operating said latch, and means actuated by said cover for preventing operation of said power controlling mechanism when the cover is opened.

6. In a safety device, a cover member, a latch device thereon, means carried by a movable part to automatically operate said latch, and a stop mechanism connected to control said movable part.

7. In a safety device, a cover member, a latch device thereon, governor controlled means carried by a moving part to automatically operate said latch, and a stop mechanism connected to control said movable part.

8. In a safety device, a cover member, a latch device thereon, means carried by a moving part to automatically operate said latch, means for automatically opening said

cover when unlatched, and a stop mechanism connected to control said movable part.

9. In a safety device, a movable cover member provided with a latch, a shaft for actuating the driven parts, a stop mechanism connected to control said shaft, shiftable means carried by said shaft, and a connection from said means to said latch.

10. In a safety device, a movable cover member provided with a latch, a shaft for actuating the driven parts, a stop mechanism connected to control said shaft, shiftable means carried by said shaft, a lever engaging said shiftable means, an actuating rod extending from said latch, and a connection between said lever and rod.

11. In a safety device, a movable cover member provided with a latch, a shaft for actuating the driven parts, a stop mechanism connected to control said shaft, shiftable means carried by said shaft, a lever engaging said shiftable means, an actuating rod extending from said latch, a rock shaft having crank arms disposed at an angle to each other, a pivoted connection from one of said levers to the latch rod, and a rod extending from the other crank lever to the lever connected to the shiftable means.

12. In a safety device, a movable cover member provided with a latch, a shaft for actuating the driven parts, a stop mechanism connected to control said shaft, shiftable means carried by said shaft, a connection from said means to said latch, a vertical pivot for said lever intermediate of its ends, and means for mounting the outer end of said lever for horizontal movement in said connection.

13. In a safety device, a movable cover member provided with a latch, a shaft for actuating the driven parts, a stop mechanism connected to control said shaft, shiftable means carried by said shaft, a connection from said means to said latch, a vertical pivot for said lever intermediate of its ends, and a horizontal loop at the lower end of said connection adapted to receive the outer end of said lever.

14. In a safety device, a pivoted cover member, a rotating shaft for a driven part, a stop mechanism connected to control said shaft, a latch pivoted upon said cover member, a governor mounted to slide upon said rotatable shaft, and a connection from said governor to said latch.

15. In a safety device, a pivoted cover member, a rotating shaft for a driven part, a stop mechanism connected to control said shaft, a latch pivoted upon said cover member, a governor mounted to slide upon said rotatable shaft, a lever engaging at one end a movable member of said governor, a swiveled pivotal support for said lever, and a connection from said lever to said latch.

16. In a safety device, a stopping mecha-

nism, a controlling lever for actuating the same, a reciprocating connection between said mechanism and lever, a movable cover member, and means from said member adapted to prevent reciprocation of said connection.

17. In a safety device, a stopping mechanism, a controlling lever for actuating the same, a reciprocating connection between said mechanism and lever, a movable cover member, a stop carried by said connection, and a locking device connected for operation by said cover to engage said stop.

18. In a safety device, a stopping mechanism, a controlling lever for actuating the same, a reciprocating connection between said mechanism and lever, a movable cover member, a stop carried by said connection, a bolt mounted for movement in the path of said stop, and a contact block actuated by said cover to engage said bolt.

19. In a safety device, a stopping mechanism, a controlling lever for actuating the same, a reciprocating connection between said mechanism and lever, a movable cover member, a stop carried by said connection, a bolt mounted for movement in the path of said stop, a spring for retracting said bolt, a sliding contact block to engage said bolt, and a connection from said block to said cover.

20. In a safety device, a stopping mechanism, a controlling lever for actuating the same, a reciprocating connection between said mechanism and lever, a movable cover member, a stop carried by said connection, a bolt mounted for movement in the path of said stop, a spring for retracting said bolt, a sliding contact block to engage said bolt, a bell crank lever connected to said block, and a connection from said lever to the cover member.

21. In a safety device for a power driven machine, a driving shaft, a pivoted cover member provided with a latch, a sliding operating rod extending from said latch, a rock shaft at the rear of said cover provided with a crank arm connected to said sliding rod, a crank arm secured to the opposite end of said rock shaft and provided with a depending rod, and a connection from said rod to said driving shaft to actuate said latch.

22. In a safety device for a power driven machine, a driving shaft, a pivoted cover member provided with a latch, a sliding operating rod extending from said latch, a rock shaft at the rear of said cover provided with a crank arm connected to said sliding rod, a crank arm secured to the opposite end of said rock shaft and provided with a depending rod, a connection from said rod to said driving shaft to actuate said latch, a lug carried by said cover, a bell crank lever loosely mounted upon said rock shaft, a con-

nnecting link between said bell crank lever and lug, a tubular member carried by said bell crank lever and surrounding said depending rod, a contact block carried by said tubular member, a stopping mechanism, and a locking mechanism mounted for actuation by said block to prevent operation of said stopping mechanism.

23. In a safety device for a power driven machine, a driving shaft, a pivoted cover member provided with a latch, a sliding operating rod extending from said latch, a rock shaft at the rear of said cover provided with a crank arm connected to said sliding rod, a crank arm secured to the opposite end of said rock shaft and provided with a depending rod, a connection from said rod to said driving shaft to actuate said latch, a lug carried by said cover, a bell crank lever loosely mounted upon said rock shaft, a connecting link between said bell crank lever and lug, a tubular member carried by said bell crank lever and surrounding said depending rod, a contact block carried by said tubular member, a locking mechanism mounted for actuation by said block, a stopping mechanism having a depending actuating rod, and a stop carried by said rod to operate with said locking mechanism.

24. In a safety device, a pivoted cover member, a latch pivotally mounted thereon, a slide rod extending from said latch, a pivotally connected link slidably mounted at the rear of said cover, and a connection from said link to actuate said latch.

25. In a safety device, a casing, a cover member pivoted thereon, means for automatically holding said cover in closed position, and means for automatically opening said cover.

26. In a safety device, a casing, a cover member pivoted thereon, means for automatically holding said cover in closed position, a flexible connection extending from said cover toward the rear of the machine, a bearing for said connection, and a tension device carried by said connection.

27. In a safety device for a power driven machine, a driving shaft for said machine, a countershaft, brake pulleys upon said driving and countershafts, a power controlling mechanism for said driving shaft, lever connections to simultaneously operate said brake and power mechanisms, a cover member provided with a latch, and means carried by said driving shaft for automatically operating said latch.

28. In a safety device for a power driven machine, a driving shaft for said machine, a countershaft, brake pulleys upon said driving and countershafts, a power controlling mechanism for said driving shaft, lever connections to simultaneously operate said brake and power mechanisms, a cover member provided with a latch, means carried by

said driving shaft for automatically operating said latch, and means actuated by said cover for preventing operation of said power controlling mechanism when the 5 cover is opened.

29. In a safety device for power driven machines, a cover member, a driving shaft, a power shifter, a brake for said shaft, connections to operate said brake simultaneously with the shifting of the power, and connections from said cover member to prevent the operation of the power shifting member when the cover is opened.

30. In a safety device for power driven machines, a cover member, a driving shaft, a power shifter, a brake for said shaft, connections to operate said brake simultaneously with the shifting of said power, and connections from said driving shaft to said

cover member for latching the same while 20 the shaft is rotating.

31. In a safety device for power driven machines, a cover member, a driving shaft, a power shifter, a brake for said shaft, connections to operate said brake simultaneously with the shifting of the power, connections from said driving shaft to said cover member for latching the same while 25 the shaft is rotating, and connections from said cover member to prevent operation of 30 the power shifter when the cover is opened.

In testimony whereof we affix our signatures in presence of two witnesses.
